GARBAGE GRINDER CONTROL MECHANISM

John Drew, Kent, Ohio, assignor to National
Rubber Machinery Company, Akron, Ohio, a
corporation of Ohio

Application April 22, 1947, Serial No. 743,013

6 Claims. (Cl. 241—63)

1

The present invention is primarily concerned with a garbage grinder control mechanism of such form that the grinding apparatus is rendered completely inoperative whenever the drain opening of the sink with which the waste receiving cavity of the grinder is in communication is uncovered by the removal of the strainer and stopper assembly therefrom, as for example during the depositing of waste into such cavity for subsequent grinding, shredding and cutting.

This invention is further concerned with a control mechanism of such form that the operating of the grinding apparatus is conditioned upon both the stopper assembly being properly positioned in the discharge opening of the sink and the valve associated with a water supply line leading to said sink being open to permit water to flow into the sink and into the waste receiving cavity of the grinding apparatus.

Control mechanisms capable of functioning generally as aforesaid are disclosed in James H. Powers Patents 2,185,037 and 2,244,402 which issued on Dec. 26, 1939 and June 3, 1941, respectively. However, it will become apparent from the ensuing description that the grinding apparatus, while under the control of a removable stopper assembly, is herein rendered operative and inoperative respectively simply by inserting and removing said stopper assembly from the discharge opening of the sink without requiring any relative rotative movements of the perforate members constituting said stopper assembly subsequent to insertion of said assembly into such discharge opening and prior to removal of the same.

Another advantage of the present control mechanism is that it is of such form that it is virtually impossible to render the grinding apparatus operative while said stopper assembly is out of such discharge opening, thereby avoiding the possibility of injury to the hand of the operator when reaching into the waste receiving cavity.

Other objects and advantages of this invention will become apparent as the following description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in

which the principle of the invention may be employed.

In said annexed drawing:

Fig. 1 is a side elevation view of a typical garbage grinder with which the improvements constituting the present invention are adapted to be used;

Figs. 2 and 3 are respectively top plan and central vertical cross sectional views of one form of stopper assembly which is adapted to be inserted into and removed from the drain opening of the sink to render the grinding apparatus operative and inoperative;

Figs. 4 and 5 are views similar to Figs. 2 and 3 except illustrating another form of stopper assembly;

Fig. 5A is a fragmentary elevation view showing the stopper assembly of Fig. 5 withdrawn from garbage grinder operating position;

Fig. 5B is an elevation view of the stopper assembly as viewed from the left-hand side of Fig. 5A; and

Figs. 6 and 7 are schematic wiring and piping diagrams illustrating two ways of rendering the grinder motor operative upon opening of a valve in a water supply line to permit water to flow into the sink and upon proper insertion of the stopper assembly and inoperative either upon closing of said valve or removal of said stopper assembly.

Referring now to the drawing and first to Fig. 1, there is shown therein the discharge opening portion of a sink 1 having connected thereto a garbage grinder or comminuting apparatus generally indicated by the numeral 2. Said apparatus is provided with a waste receiving cavity 3 within which an impeller 4, rotated by an electric motor 5, is operative to comminute refuse deposited into cavity 3. With the assistance of water flowing into cavity 3 from the sink, such refuse is flushed and carried away to a sewer or the like through the discharge pipe 6. The detailed construction and operation of said apparatus is fully explained in co-pending application, Serial No. 730,930 of Allen L. Heston et al., filed Feb. 26, 1947, now abandoned, of which I am one of the co-inventors.

The connection between sink 1 and apparatus 2 is herein illustrated as comprising a collar 7 having a neck portion passing downwardly through the discharge opening of the sink and a radially outwardly projecting flange portion overlying the upper surface of the sink. The lower end of collar 7 has threaded engagement with apparatus 2. A plurality of circumferen-

tionally spaced bolts 8, having threaded engagement with apparatus 2, are operative to urge an annular sealing gasket 9 into sealed engagement with both the bottom surface of the sink and the outer surface of the neck portion of collar 7. In order to obtain uniform clamping pressure around the entire sink opening, a metal ring 10 is interposed between gasket 9 and the heads of bolts 8.

Before discussing in detail the structure of the stopper assemblies herein illustrated and the manner in which they render the motor 5 of the comminuting apparatus operative and inoperative, reference will be made to the piping and wiring diagrams of Figs. 6 and 7. In Fig. 6 there are two valves 11 and 12, each of which has its out-fall side leading to the sink either separately or else as shown through the common discharge spout 13, valve 11 being connected to a hot water supply line 14 and the valve 12 being connected to a cold water supply line 15. Connected in the cold water line 15 ahead of valve 12 is a flow responsive device 16 which is in the nature of a check valve having a valve member 17 therein movable away from its seat in response to the pressure differential caused by opening of the valve 12. Said valve member 17 is moved into engagement with its seat in response to closing of the valve 12 and the resulting equalization of the pressures on opposite sides of said valve member. When valve member 17 moves upwardly away from its seat, the engagement of the upper end therein with a pivoted lever and arm assembly 18 effects rotation of such arm assembly in a direction permitting closing of switch 19 which is in series with motor 5. A switch 20 also in series with motor 5 is operated in a manner as will be described by the proper placing of one of the novel stopper assemblies illustrated in Figs. 2-5B into the sink opening.

From Fig. 6 it will be apparent that the motor 5 is rendered operative only when both switches 19 and 20 are closed and inoperative when either or both of said switches are opened. In the present case switch 19 can only be closed when water is actually flowing through the flow responsive device 16 through the valve 12 into the sink and switch 20 can only be closed when the stopper assembly is properly positioned in the sink opening.

The piping and wiring diagram of Fig. 7 is substantially the same as that of Fig. 6 except that the flow responsive device 16 has been omitted and instead thereof a cam 21 on the stem of valve 12 engages and disengages the push button of switch 19 to respectively close and open said switch when valve 12 is turned on and off. Here again, as in Fig. 6, the motor 5 of the comminuting apparatus 2 can only be operated when both of the switches 19 and 20 are closed, such closing being effected by opening of valve 12 to permit water to flow into the sink and properly inserting the stopper assembly into the sink opening.

It is to be understood that the flow responsive device 16 and switch 19 in Fig. 6 or cam 21 and switch 19 in Fig. 7 may be omitted altogether, if desired, to thus render the motor 5 operative and inoperative simply by opening and closing switch 20. Also, if desired, the valve 12 and the flow responsive device 16 may be piped in parallel with cold water line 15, in which case another valve may be installed in line 15 to permit water to flow into the sink without effecting closing of switch 19. Such modification is disclosed in co-

pending application Serial No. 743,398, filed April 23, 1947, by Paul A. Frank.

In the stopper assembly shown in Figs. 2 and 3, the collar 7 is formed with an inturned flange 23 at its lower end which is adapted to be engaged by the out-turned flange 24 formed on the upper perforated member 25 of the stopper assembly, such engagement of the flanges functioning as a stop when said assembly is inserted into the sink opening. Said member 25 is formed with a cylindrical recess into which fits the lower perforate member 26, said members being rotatable relative to one another to selectively open and close communication between the sink 1 and the waste receiving cavity 3 of the comminuting apparatus when said stopper assembly is in the sink opening. Said members 25 and 26 are rotated relative to one another by means of a handle 27 which has its downwardly depending legs 28 extending through the segmental openings 29 in the upper member 25 and secured as by screws 30 to the segmental arms 31 of the lower member 26. A spring 32 fitted into a downwardly opening recess in handle 27 is operative through a disc 33 pressed against the upper surface of member 25 by said spring to urge the abutting faces of members 25 and 26 into engagement. When it is desired to rotate members 25 and 26 relative to one another, handle 27 is preferably pressed downwardly to disengage said abutting faces, whereupon the friction between flanges 23 and 24 will be greater than that between disc 33 and member 25, whereby the lower member 26 may be rotated relative to the upper member 25. In the position shown in Fig. 2, members 25 and 26 are set to permit flow of water from the sink 1 into the waste receiving cavity 3 of comminuting apparatus 2. The upper member 25 is formed with a longitudinally extending projection 34 which, as will be seen, is operative to actuate the switch 20 mounted on one side of the upper portion of the housing of the comminuting apparatus 2 when the stopper assembly is properly inserted into the sink opening.

Fitted into a bore through the side wall of apparatus 2 is a bushing member 35 which has its longitudinal axis disposed radially of the sink opening and which has reciprocably mounted therein a pin 36 which is suitably sealed in the bushing as by a packing ring 37 of synthetic rubber or like material. The outer end of said pin 36 is attached to a cantilever spring member 38 which has one end thereof attached as by a screw 39 to the housing of the comminuting apparatus. The other end of spring member 38 is adapted to engage the push button of switch 20 in such a manner that when said pin 36 is shifted radially outward of the sink opening, said switch is closed and then, upon release of the force which so moves the pin, the spring member 38 will be effective to move said pin radially inward, the movement of spring member 38 permitting opening of switch 20. The rounded inner end of said pin 36 projects part way, as indicated by the dotted line of Fig. 3, into a bore transverse of the bushing 35 and parallel to the axis of the sink opening, such bore being adapted to receive the projection 34 on the stopper assembly. It is thus apparent that when the stopper assembly is positioned in the sink opening so that the projection 34 enters the bore in the bushing, the pin 36 will be forced radially outward to effect closing of switch 20 as just described and likewise, upon removal of the stopper assembly from the sink opening, the projection 34 will be withdrawn from

such bushing bore whereby spring member 38 will be operative to permit opening of switch 20. With the arrangement shown, the switch 20 cannot be accidentally closed to start motor 5 because the transverse bore in the bushing is so small that even an infant's fingers cannot be inserted therewith to actuate pin 36.

When the stopper assembly is used to render the comminuting apparatus operative, as just explained, the three dots 40 on the flange of collar 7 on member 25 and on handle 27 should be in alignment, as shown in Fig. 2, whereupon water may freely flow from the sink into the waste receiving cavity 3. As previously described, the valve 12 in Figs. 6 and 7 must be opened before motor 5 can be started.

When it is desired to use the sink in its ordinary manner without operating the comminuting apparatus, the stopper assembly is positioned in the sink opening so that projection 34 thereon does not enter the transverse bore of bushing 35. In such case the members 25 and 26 of the stopper assembly may be rotated relative to one another to either close or open communication between the sink and the waste receiving cavity 3 as desired, it then being impossible to start motor 5.

Referring now to the stopper assembly of Figs. 4, 5, 5A, and 5B wherein the parts similar to those shown in Figs. 2 and 3 are indicated by like numerals, the inturned flange 23 of collar 7 is interrupted at two circumferentially spaced points 23A and 23B and members 25 and 26 are each provided with a protuberance 41 and 42, respectively, of such shape that the stopper assembly can only be positioned into the sink opening when such protuberances are in alignment with one another and in register with one or the other of the interruptions 23A or 23B in flange 23. Furthermore, such protuberances are arranged so that when they are in alignment the flow openings through the stopper assembly are maximum. In such position the legs 28 of handle 27 engage the adjacent edges of the segmental openings in upper member 25 to function as a stop to limit relative rotation of members 25 and 26 to a position wherein such protuberances are in alignment.

When the stopper assembly is lowered from the position in Fig. 5A and positioned in the sink opening to the "on" position, as shown in Figs. 4 and 5, the projection 34 will, as described in relation to Figs. 2 and 3, effect radial outward shifting of pin 36 to close switch 20. In this position both of the members 25 and 26 are non-rotatably locked in the sink opening by engagement of protuberances 41 and 42 with one notch in flange 23 and also by engagement of projection 34 in the opening in member 35 whereby it is not possible to close the flow openings through the stopper assembly and thus operate the comminuting apparatus without any water flow therethrough. When it is desired to render the comminuting apparatus inoperative, all that it is necessary to do is to longitudinally withdraw the stopper assembly to thus effect withdrawal of the projection 34 from the bushing 35 and the consequent opening of the switch 20.

On the other hand, when it is desired to use the sink in its usual manner without effecting starting of motor 5, the stopper assembly is simply positioned in the sink opening so that the protuberances 41 and 42 are at the position marked "off." In such case the engagement of protuberance 41 with the interrupted portion 23B of the inturned flange 23 serves to non-rotatably lock

member 25 in the sink opening and in such position the protuberance 42 is clear of such interruption, whereupon member 26 may be rotated to any position between "off" and "seal." Such rotation of member 26 operates to lock the entire stopper assembly against longitudinal withdrawal from the sink. In such rotated position of member 26, the protuberance 42 underlies the flange 23 so that the stopper assembly is locked against withdrawal from the sink. Removal of the stopper assembly can only be effected by rotating member 26 until its protuberance 42 is in alignment with protuberance 41 and the interrupted portion 23B in the inturned flange 23.

Handle 27 is preferably provided with an arrow 43 thereon which cooperates with markings on the flange of collar 7 to indicate the "on" and "off" positions of the comminuting apparatus, in which case the flow openings through the stopper assembly are fully opened and the "seal" position of the stopper assembly in which case the flow openings through the stopper assembly are closed and the motor 5 is not in operation.

By way of summary, it can be seen that with either form of stopper assembly herein disclosed the comminuting apparatus is rendered operative and inoperative simply by longitudinally inserting the stopper assembly into the sink opening and longitudinally removing the stopper assembly from the sink opening. In another position of the stopper assembly insertion and removal of the stopper assembly has no effect on the operation of the comminuting apparatus.

Other modes of applying the principle of the invention may be employed, change being made as regards the details described, provided the features stated in any of the following claims or the equivalent of such be employed.

I therefore particularly point out and distinctly claim as my invention:

1. The combination with a comminuting apparatus provided with a passage leading thereto, such passage being radially constricted adjacent its outer end to form a seat, a comminuting member in such passage inward of such seat, a motor for driving said member, and a switch inwardly adjacent such seat controlling energization of said motor, of an actuator for said switch selectively insertable axially into such passage in any of a plurality of rotative positions, said actuator being provided with a radially projecting flange forming a seat engageable with the seat in such passage and with a cam portion clearing said switch in one rotative position and engaging and actuating said switch in another rotative position, said actuator comprising a pair of adjacent, relatively rotatable disk members formed with openings therethrough in and out of registry with one another in accordance with the relative rotative positions of said members, and a handle for relatively rotating said members including a leg projecting through the opening in one of said members and connected to the other of said members, the seat in such passage including a pair of circumferentially spaced notches, and each of said members including a corresponding protuberance which is aligned with the protuberance of the other of said members when said members are in a position with the openings therethrough in registry, one of such notches being formed to embrace the aligned protuberances of said actuator in one rotative position of the latter and thereby lock said members against relative rotation to a position with such openings out of registry.

2. The combination with a comminuting apparatus provided with a passage leading thereto, such passage being radially constricted adjacent its outer end to form a seat, a comminuting member in such passage inward of such seat, a motor for driving said member, and a switch inwardly adjacent such seat controlling energization of said motor, of an actuator for said switch selectively insertable axially into such passage in any of a plurality of rotative positions, said actuator being provided with a radially projecting flange forming a seat engageable with the seat in such passage and with a cam portion clearing said switch in one rotative position and engaging and actuating said switch in another rotative position, said actuator comprising a pair of adjacent relatively rotatable disk members formed with openings therethrough in and out of registry with one another in accordance with the relative rotative positions of said members, and a handle for relatively rotating said members including a leg projecting through the opening in one of said members and connected to the other of said members, the seat in such passage including a pair of circumferentially spaced notches, and each of said members including a corresponding protuberance which is aligned with the protuberance of the other of said members when said members are in a position with the openings therethrough in registry, one of such notches being formed to embrace the aligned protuberances of said actuator in one rotative position of the latter and thereby lock said members against relative rotation to a position with such openings out of registry, and the other of such notches being formed to embrace the protuberance on said one of said members and to clear the protuberance on said other of said members in a different rotative position of said actuator whereby the latter member may be rotated relative to the former member to a position with such openings in said members out of registry with one another.

3. The combination with a comminuting apparatus provided with a passage leading thereto, such passage being radially constricted adjacent its outer end to form a seat, a comminuting member in such passage inward of such seat, a motor for driving said member, and a switch inwardly adjacent such seat controlling energization of said motor, of an actuator for said switch selectively insertable axially into such passage in any of a plurality of rotative positions, said actuator being provided with a radially projecting flange forming a seat engageable with the seat in such passage and with a cam portion clearing said switch in one rotative position and engaging and actuating said switch in another rotative position, said actuator comprising a pair of adjacent relatively rotatable disk members formed with openings therethrough in and out of registry with one another in accordance with the relative rotative positions of said members, and means for relatively rotating said members, the seat in such passage including a pair of circumferentially spaced notches, and each of said members including a corresponding protuberance which is aligned with the protuberance of the other of said members when said members are in a position with the openings therethrough in registry, one of such notches being formed to embrace the aligned protuberances of said actuator in one rotative position of the latter and thereby lock said members against relative rotation to a position with such openings out of registry, and the other of such notches being formed to embrace the protuberance on one of said members and to clear the protuberance on the other of said members in a different rotative position of said actuator whereby the latter member may be rotated relative to the former member to a position with such openings in said members out of registry with one another.

8
said members against relative rotation to a position with such openings out of registry.

4. The combination with a comminuting apparatus provided with a passage leading thereto, such passage being radially constricted adjacent its outer end to form a seat, a comminuting member in such passage inward of such seat, a motor for driving said member, and a switch inwardly adjacent such seat controlling energization of said motor, of an actuator for said switch selectively insertable axially into such passage in any of a plurality of rotative positions, said actuator being provided with a radially projecting flange forming a seat engageable with the seat in such passage and with a cam portion clearing said switch in one rotative position and engaging and actuating said switch in another rotative position, said actuator comprising a pair of adjacent relatively rotatable disk members formed with openings therethrough in and out of registry with one another in accordance with the relative rotative positions of said members, and means for relatively rotating said members, the seat in such passage including a pair of circumferentially spaced notches, and each of said members including a corresponding protuberance which is aligned with the protuberance of the other of said members when said members are in a position with the openings therethrough in registry, one of such notches being formed to embrace the aligned protuberances of said actuator in one rotative position of the latter and thereby lock said members against relative rotation to a position with such openings out of registry, and the other of such notches being formed to embrace the protuberance on one of said members and to clear the protuberance on the other of said members in a different rotative position of said actuator whereby the latter member may be rotated relative to the former member to a position with such openings in said members out of registry with one another.

5. The combination with a comminuting apparatus formed with a passage therethrough providing at one end an inlet for the introduction of refuse to be comminuted and at the other end an outlet for the discharge of comminuted refuse, a comminuting member movable in such passage, a motor for driving said member, and a switch controlling energization of said motor, of an actuator for said switch selectively insertable axially into such passage at the inlet end thereof in any of a plurality of rotative positions, said actuator constituting the inlet closure for said apparatus and being provided with drain openings for flow of water into said apparatus, said actuator including a prong projecting therefrom in the direction of axial insertion of said actuator into such passage, and a member in said apparatus extending radially into such passage and provided with an opening disposed parallel to such prong and of a cross-section size to preclude insertion of an infant's fingers thereinto, such prong extending into such opening in one rotative position of said actuator in such passage, and a switch operating element having an end portion extending transversely into such opening and embraced by the portion of said member which surrounds such opening to thereby render said element inaccessible for operating said switch except through such opening, said element being engaged and moved by such prong when the latter is inserted into such opening as aforesaid for thereby operating said switch and energizing said motor.

6. The combination with a comminuting apparatus formed with a passage therethrough providing at one end an inlet for the introduction of refuse to be comminuted and at the other end an outlet for the discharge of comminuted refuse, a comminuting member movable in such passage, a motor for driving said member, and a switch controlling energization of said motor, of an actuator for said switch selectively insertable axially into such passage at the inlet end thereof in any of a plurality of rotative positions, said actuator including a cam portion clearing said switch in one rotative position and engaging and actuating said switch in another rotative position, said actuator comprising a pair of relatively movable members operative when said actuator is in such passage to open and close communication between opposite sides of said actuator, means for locking said members in open position against relative movement to closed position and non-rotatably locking said actuator in such passage upon insertion of said actuator into such passage to engage and actuate said switch and for locking said actuator from axial withdrawal from such passage upon relative movement of the members thereof from open toward closed position after said actuator has been inserted into such passage to clear said switch, said last-named means comprising an inturned flange providing a seat for said actuator, which flange is formed with a pair of cir-

10
